UNITED STATES PATENT OFFICE

155,574

DESIGN FOR A COMBINED RACK AND POT HOLDERS OR SIMILAR ARTICLE

Samuel Brodsky, Brooklyn, N. Y.

Application October 29, 1947, Serial No. 142,187

Term of patent 14 years

(Cl. D44—24)

To all whom it may concern:

Be it known that I, Samuel Brodsky, a citizen of the United States, and a resident of Brooklyn, in the county of Kings, and State of New York, have invented a new, original, and ornamental Design for a Combined Rack and Pot Holders or Similar Article, of which the following is a specification, reference being had to the accompanying drawing, forming part thereof.

Figure 1 of the drawing is a front elevation of a combined rack and pot holders, showing my new design.

Figure 2 is a side elevation thereof, looking from the right of Figure 1.

Fig. 3 is a front elevation of the rack alone.

As viewed from the left of Figure 1, the design is the same as shown in Figure 2 but of opposite hand.

I claim:

The ornamental design for a combined rack and pot holders or similar article, substantially as shown and described.

SAMUEL BRODSKY.
